UNITED STATES PATENT OFFICE.

JAY CLAY DAVIS, OF MARSHFIELD, WISCONSIN, ASSIGNOR OF ONE-HALF
TO GEORGE SUEBERT, OF SAME PLACE.

WHIFFLETREE-HOOK.

SPECIFICATION forming part of Letters Patent No. 380,621, dated April 3, 1888.

Application filed May 14, 1887. Serial No. 238,271. (No model.)

To all whom it may concern:

Be it known that I, JAY CLAY DAVIS, of Marshfield, in the county of Wood and State of Wisconsin, have invented a new and useful Improvement in Whiffletree-Hooks, of which the following is a specification.

This invention is an improvement in that class of devices for attaching tugs to whiffletrees and the yoke-strap to the neck-yoke in which a ring or cockeye on the strap encircles the yoke or the whiffletree.

The invention consists in certain features of construction and novel combinations of parts, as will be described, whereby the attachment may be easily effected, and will, when in use, be secure from unfastening.

For the purpose of illustration the invention is herein shown in its application to a whiffletree, and the following description will refer to its said use; but while it is so described and while the appended claim includes a clause specifying said use, it is obvious that it is desired to protect the invention when employed on neck-yokes and in analogous relations.

In the said drawings, Figure 1 is a top plan view of a section of a whiffletree provided with my invention, the cockeye being shown fastened in full lines, and dotted lines being employed to indicate its position for removal from the loop. Fig. 2 is a detail rear view of the loop. Fig. 3 is a detail perspective view of the invention, the cockeye being shown in fastened position; and Fig. 4 shows a slightly different construction.

The securing loop or keeper A is extended longitudinally, and has a supporting-plate, B, which may be a plate partly encircling the whiffletree or bar C, but is preferably a thimble to fit thereon, as will be understood from the drawings. This keeper is divided by a slot, a, which is formed diagonally to the length of

the keeper, and is arranged, preferably, about midway between its ends, as shown.

The supporting-plate may be secured to the 45 whiffletree in any suitable manner, with the loop or keeper A on the rear side thereof, or on the side of said whiffletree or bar C opposite that to which the strap attached to cock-eye D is extended.

The cockeye D may have the eye proper, d, and the loop d', the former being adapted to fit over the end of the whiffletree and the latter to facilitate the attachment of the tug, yoke, or other strap. In use the eye may be 55 adjusted to the dotted position shown, and then be moved through slot a into and out of the loop A. When the cockeye is in the full-line position shown in Fig. 1, it will be securely held.

In Fig. 4 the slot or opening into the keeper or loop is formed at one end of the said loop, so that the cockeye can only move in one direction within the loop from said slot.

This construction may be preferred for singletrees, while that shown in Figs. 1, 2, and 3 may be preferred on poles and tongues for securing the neck-yokes.

Having thus described my invention, what I claim as new is—

As an improved article of manufacture, the described attachment for whiffletrees and similar bars, the same consisting of a loop having a slot dividing and leading into it, such slot being formed or extended in a line diagonal to 75 the direction of length of the loop, and a supporting-plate adapted for connection with said whiffletree or bar, substantially as and for the purposes specified.

JAY CLAY DAVIS.
